UNITED STATES PATENT OFFICE

128,067

DESIGN FOR A COMBINED STAND, MIRROR, AND CONTAINERS FOR PERFUMERY, OR THE LIKE

Robert B. Karoff, New York, N. Y.

Application April 28, 1941, Serial No. 100,650

Term of patent 3½ years

To whom it may concern:

Be it known that I, Robert B. Karoff, a citizen of the United States, residing at New York, in the city, county and State of New York, have invented a new, original and ornamental Design for a Combined Stand, Mirror, and Containers for Perfumery or the Like of which the following is a specification, reference being had to the accompanying drawing, forming part thereof, wherein the figure is a front view in perspective of a combined stand, mirror, and containers for perfumery or the like, showing my new design.

I claim:

The ornamental design for a combined stand, mirror, and containers for perfumery, or the like, substantially as shown.

ROBERT B. KAROFF.
